UNITED STATES PATENT OFFICE.

LEO S. ROBINSON, OF ALAMEDA, CALIFORNIA.

METHOD OF SEGREGATING UNITS.

1,223,113.

Specification of Letters Patent. Patented Apr. 17, 1917.

Application filed January 30, 1913. Serial No. 745,194.

To all whom it may concern:

Be it known that I, LEO S. ROBINSON, a citizen of the United States, and a resident of the city of Alameda, county of Alameda, and State of California, have invented new and useful Improvements in the Method of Segregating Units, of which the following is a specification.

This invention relates to improvements in card systems or the like and the method of segregating the units therein according to the designation thereof.

An object of my invention is to provide means for readily designating the cards or units in the system according to desired sub-classifications.

A further object is to provide means for segregating from the mass of units, each and every unit bearing a common designation or designations.

Another object is to so designate each card that it is adapted to be segregated manually, or by electric or other counting or segregating machines, automatic, or otherwise.

Another object is to provide a segregating system adapted to the segregating of cards, stencils, matrices, and other units having physical characteristics adaptable to differentiation in accordance with this invention.

This invention possesses other advantageous features that, with the foregoing will be set forth at length in the following description, wherein I shall outline in full that form of the invention selected for illustration in the drawings accompanying and forming part of the present specification. The novelty of the invention will be included in the claims succeeding said description.

From this it is apparent that I do not restrict myself to the disclosure made by said drawings and description, as I may adopt many variations within the scope of my invention as expressed in said claims.

For convenience in disclosing some of the adaptations of this invention, the following description and the drawings will be confined to its application to card systems; but I do not wish to be understood as confining myself to this particular application, or the construction or arrangement of parts particularized therein.

In the drawings:

Figure 1 is a plane or face view of a blank, 55 shown for convenience as a flat card, ready

to receive modified designating subclassification openings or apertures in accordance with this invention.

Fig. 2 is a similar view of the same, having certain of its original openings elongated or varied, to give it a certain distinguishing designation or combination of distinguishing subclassifications.

Fig. 3 is an isometrical perspective in front elevation of one available means for 65 segregating all cards or the like in the mass having common single or combinative sub-classifications.

Fig. 4 is a view similar to Fig. 2, showing a modified form of perforation adaptable to 70 a modified means of segregation.

Fig. 5 is a modified form of card having a metal bound edge and vertical guide slots to receive glide rods.

Fig. 6 is an isometrical perspective of a 75 stack of cards, certain of the cards being broken away to disclose the relation of the associated cards and their subclassification designations engaging the retaining means.

In detail the construction consists of the 80 blank text card 1 preferably having one corner cut away as at 2 as a ready means of detecting a reversed card in the stack. This text card is preferably provided with the systematically spaced master holes, openings, or apertures 3, coinciding with similar holes in the key card, hereinafter described. These master openings engage the rods to prevent undesignated cards from responding to the operation of segregation herein- 85 after described; and they act as a guide or pilot-hole in the subsequent operation of elongation, slotting, notching, or other enlargement. These cards are preferably uniform in size and of conventional dimension. 90

The key card 4 has the holes 5 arranged to coincide with the master holes 3 in the cards. Each hole 5 may be given a designating title in accordance with the nature of the data to be classified by the cards. The shape 100 and position of the holes in the key card remain unaltered.

The text cards 1 may be distinguishingly designated by enlarging or elongating certain of the master holes therein depending 105 upon the desired designation; for instance, the card illustrated in Fig. 2 has certain of its original master holes altered to form enlarged apertures 3a, and by comparison with the key card it is seen that the card desig- 110

nates a certain person as being a white male, registered as a Republican and voting in ward 3, precinct 9. This description can be extended to the full capacity of the card by 5 enlarging as many master holes as desired, augmented by text matter written on the face of the card.

The invention is practised as follows: The text cards are stacked face to back in 10 alinement. To segregate all the individual text cards bearing any one or all of the six items of description above, the key card is alined in front of the stack and the segregation rod 6 is inserted in the hole designated 15 "Wht." (abbreviation for white) or all the segregation rods 7, 8, 9, 10 and 11 may be inserted in the respective holes bearing titles on the key card, corresponding with the desired items of information. With these 20 rods inserted through the whole stack, the cards are inverted, agitated or manipulated causing all of the cards having slots engaged by all of the rods to extend outward the limit of the slot, exposing a margin of 25 card beyond the edge of the stack; those cards not having slots engaging all of the rods will be held *en masse* by the rods engaging the master holes therein. With the 30 segregated cards hanging suspended on the segregation rods, one or more support rods 12 and 13 can be inserted above them to hold the margins exposed when the stack is restored to the upright position; as shown in Fig. 3. If it is desired to remove the 35 segregated cards, all the rods except the rods 12 and 13 can be removed. If only one item of information is wanted, one segregation rod is inserted in the designated hole in the key card, and every card designated with an 40 enlarged master hole corresponding to that particular item will respond to the segregating operation described. The many ramifications in the application of this invention and its adaptability to many and 45 varied classifications, and sub-classifications, is sufficiently apparent. Inverting the cards to accomplish segregation is the preferable method but other methods can be employed without departing from the spirit of this invention.

By placing in juxtaposition suitably shaped contacts in electrical counting or segregating machines, the slotted cards can be divided out of the stack according to their 55 peculiar designated sub-classifications in an obvious manner, or the enlarged holes may be adapted to other means of automatic mechanical segregation.

A modification of this invention is shown 60 in Fig. 4 in which the stack of cards are strung on a rod extended through the pivot hole 14, and the designation slots 15 are cut approximately concentric with this pivot hole. This is a convenient means for segregating the cards without other mechanical

aids than the rods. The slotted cards responding to the classification rods, swing outward from the stack on the pivot rod.

The nethermost holes 16 are preferably reserved for those classifications, in connection with which it is desired that cards bearing such data be removed entirely from the stack. In the operation of segregation, those cards which are designated by extending the hole to the margin of the card as at 75 17 are not retained by the segregation rods inserted therein and can fall free of the stack or mass of cards, in the act of segregation. One or more of these nether holes 80 must be retained to receive the support rods 12 and 13, if their function is required, and no container is used.

When it is desired to provide master holes in the card in such numbers that the texture of the card may be weakened to an 85 undesirable extent, the card can be reinforced with fabric, metal or other additions. Additional holes may be provided by a series of wire loops, perforated tabs, or the like, added to the edge of the card, and the 90 removal or cutting open of such loops or tabs would release from the retaining means the card or cards so designated, in the same manner as the enlargement of the master 95 holes, before described, and is in full accordance with the spirit of this invention and the claims forming part of this specification, so long as the means permit the designated 100 cards to separate from the stack or mass of cards, by differentiated engagement or disengagement with the retaining means.

The card illustrated in Fig. 5 is designed to overcome frictional coherence of the cards in the stack during the operation of segregation. The metal or reinforcing edging 18 105 keeps the surfaces of the cards from bearing against or chafing each other, besides adding to the strength of the card. The slots 19 may be provided in the cards and they may be strung on the rods 20 fastened 110 between the ends of the trays, drawers, or framework *x*, for containing the stack of cards. These slots act as guides to prevent lateral displacement, wedging or jamming of the cards in segregation, by causing the 115 lateral edges to move parallel in separating from the stack.

Suitable mechanical means, such as trays, drawers, and the like, may be provided to facilitate the manipulation of cards treated 120 in accordance with this invention, without departing from the spirit thereof; and the manner of enlarging, altering or placing the designating or classification holes may be varied to suit particular practices of this invention, and I do not wish to be understood as confining myself to the particular disclosures illustrated and above described.

I claim:

1. The method of classifying units, con- 125

- sisting of providing said units with master apertures, and enlarging said master apertures in any unit without breaking the edge of said unit for sub-classification.
- 5 2. The method of segregating units consisting of providing said units with master apertures, enlarging said apertures in any unit without breaking the edge of said unit and associating said units with a key member; whereby said units may be identified and segregated according to their enlarged apertures.
- 15 3. The method of segregating a designated unit or units from a plurality of associated units, consisting in perforating all the units, altering one or more perforations of the designated units, and inserting a rod or rods through all of said units; whereby the undesignated units are held, and the 20 designated units may be partially or wholly separated from said plurality of units.
- 25 4. The method of segregating cards from a plurality of cards, consisting of providing each of said cards with a series of master apertures, varying certain of said apertures, inserting a rod or rods through all of said cards, and subsequently effecting segregation by means of the variations of said apertures engaging said rod or rods.
- 30 5. The method of classifying and segregating units, consisting of providing said units with master apertures, enlarging one or more of said master apertures, to represent classification or subclassification, and 35 passing segregation means through said apertures; whereby designated units may be selected from a plurality of units, according to all of the enlarged master apertures acted upon by the segregation means.
- 40 6. The method of segregating a unit or units from a plurality of associated units, consisting of providing all of said units with aligned apertures, some of said apertures being of greater area than the others, 45 passing retaining means through one or more of said apertures, and manipulating the associated units; whereby the units having apertures of greater area engaging said retaining means, may extend beyond the 50 marginal alignment of the mass of associated units.
- 55 7. The method of segregating a unit or units from a plurality of associated units, consisting of providing all of said units with master apertures enlarging certain of the master apertures in designated units, placing said units in a container, having apertures registering with said master apertures in the units, inserting retaining rods 60 through the registering apertures in the container and the units, and inverting the container; whereby the designated units may be segregated from the mass of units, the limit of the enlargement of their master 65 apertures engaging the said retaining rods.
8. The method of segregating a unit or units from a plurality of associated units, consisting of providing all of said units with master apertures enlarging certain of the master apertures in designated units, inserting said units in a container having apertures registering with said master apertures in the units, inserting retaining rods through the registering apertures in the container and the units, and inverting the 70 container; whereby the designated units may be segregated from the mass of units, the limit of the enlargement of their master holes engaging said retaining rods; then inserting support rods through the container and the mass of units, beneath the segregated units, and restoring the container to the normal position.
- 75 9. The method of segregating designated units from a plurality of units, among which they are variously interspersed, consisting of providing all of the units with uniform master apertures, enlarging one or more of said apertures, as information is added to each unit to identify it under several classifications, to facilitate its selection mechanically, under any one or more classifications represented by the enlarged apertures therein.
- 80 10. The method of sorting units from a number of associated units, having differentiating characteristics within the margin of the units, which comprises engaging the units not having the desired differentiating characteristics, by one or more separate engaging means; and moving with respect thereto the units not so engaged.
- 85 11. A method of sorting cards according to information appearing thereon, which comprises arranging the cards on edge with aligned parts of the cards each allotted to a particular item of information appearing on some of the cards and with each of said parts of each card allotted to an item not appearing thereon equipped for engagement with engaging means co-acting with said part, associating with the cards a plurality of separate engaging means, each adapted to co-act with the equipment at one of said parts of each card, and moving 100 relative to the mass the cards not retained with the mass by any of said engaging means.
- 105 12. A method of sorting cards according to a plurality of items of information contained thereon, comprising arranging the cards in a mass, equipping each card for movement relative to the mass with respect to items of information contained on said card and for engagement at one or more of a plurality of points each representing an item not contained on said card but contained on other cards, associating therewith a plurality of separate means each adapted 110 to engage the cards at one of said points 115
- 120 13. A method of sorting cards according to a plurality of items of information contained thereon, comprising arranging the cards in a mass, equipping each card for movement relative to the mass with respect to items of information contained on said card and for engagement at one or more of a plurality of points each representing an item not contained on said card but contained on other cards, associating therewith a plurality of separate means each adapted 125 to engage the cards at one of said points 130

and to hold the cards with the mass when so engaged, and moving relative to the mass the cards not retained with the mass by any of said engaging means.

13. A method of sorting cards according to a plurality of items of information appearing thereon, comprising arranging the cards vertically in a mass with aligned parts of all the cards allotted to particular items of information and equipped with means for retention or freedom from such retention with members co-acting with said part of all the cards according to the absence or presence of that item on said cards, associating therewith a series of members each adapted to co-act with the said equipment at one of said parts of the cards to retain with the mass the cards equipped at said part with means for retention by the members and to permit cards not so equipped to move relative to the mass, and moving relative to the mass the cards not retained with the mass by any of said members.

14. A method of sorting units according to a plurality of characteristics, which comprises associating therewith a plurality of separate engaging means each allotted to a particular characteristic of some of the units and adapted to engage each unit or leave it free from engagement thereby according to the absence or presence of the particular characteristic to which said engaging means is allotted, and moving relative to the engaged units those units not engaged by any of said engaging means, whereby the units having the plurality of

characteristics to which the actuated engaging means are allotted are differentiated and may be separated from the other units.

15. A method of sorting units from a number of associated units according to a plurality of characteristics, which comprises engaging the units not having any of the plurality of characteristics according to which it is desired to make the selection by one or more separate engaging means each representing one distinct characteristic of the plurality according to which it is desired to make the selection, holding said units by means of one or more of said engagements and moving with respect thereto to the units not so engaged, whereby the units having said plurality of characteristics are differentiated and may be separated from the units having none of said characteristics.

16. The method of segregating units consisting of providing said units with master apertures; removing material between certain of said apertures; and passing retaining means through said apertures in the units, whereby said units having material removed between the apertures may be moved with respect of the cards not having material so removed.

In testimony whereof, I have hereunto set my hand at San Francisco, California, this 24th day of January, 1913.

LEO S. ROBINSON.
